UNITED STATES PATENT OFFICE.

IVAN GROZEJ, OF MCKEESPORT, PENNSYLVANIA, ASSIGNOR OF ONE-FIFTH TO MIJO PAUSIC, ONE-FIFTH TO FRANJO GRDIC, ONE-FIFTH TO PETAR GRDIC, AND ONE-FIFTH TO NIKOLA BOKULIC, OF MCKEESPORT, PENNSYLVANIA.

RAIL-JOINT.

1,146,494.

Specification of Letters Patent.

Patented July 13, 1915.

Application filed February 27, 1915. Serial No. 11,112.

To all whom it may concern:

Be it known that I, IVAN GROZEJ, a subject of the King of Hungary, residing at McKeesport, in the county of Allegheny and State of Pennsylvania, have invented certain new and useful Improvements in Rail-Joints, of which the following is a specification.

This invention relates to rail joints and has for its object to provide means in a manner as hereinafter set forth for connecting the opposing ends of a pair of track rails together, without the employment of nuts and bolts, at the same time providing for the necessary contraction and expansion of the track rails due to climatic influences.

Further objects of the invention are to provide a rail joint which is comparatively simple in its construction and arrangement, strong, durable, efficient and convenient in its use, readily set up and comparatively inexpensive to manufacture.

With the foregoing and other objects in view the invention consists of the novel construction, combination and arrangement of parts as hereinafter more specifically described and illustrated in the accompanying drawing, wherein is shown an embodiment of the invention, but it is to be understood that changes, variations and modifications can be resorted to which come within the scope of the claim hereunto appended.

In the drawings wherein like reference characters denote corresponding parts throughout the several views:—Figure 1 is a side elevation of a rail joint in accordance with this invention. Fig. 2 is a top plan. Fig. 3 is a section on line X—X, Fig. 1. Fig. 4 is a section on line Y—Y, Fig. 1.

Referring to the drawings in detail 1 and 2 denote a pair of track rails and each of which consists of a head 3, web 4, and base 5.

Each of the webs 4, at one end, is formed centrally thereof with a longitudinally extending slot 6 opening at the edge of the web and the latter is furthermore provided with a centrally disposed longitudinally extending opening 7, spaced from the inner wall of the slot 6, but arranged in alinement thereof, and of less width than the width of the slot 6.

The reference character 8 denotes a splice

bar, which when in position is arranged against one side of the webs 4 of the track rails 1, 2. The splice bar 8 has projecting from its inner face a right angularly disposed longitudinally extending tongue 9, which projects through alining slots 6 when the track rails 1, 2, are positioned as illustrated in Fig. 1. When the slots 6 are in alinement, the open end of the slotted rail 1 registers with the open end of the slotted rail 2. The splice bar 8 has its inner face furthermore provided with a pair of projections 10, which are spaced from the ends of the tongue 9 and when the splice bar 8 is mounted in position, as stated, the said projections 10 extend through the openings 7.

Positioned against the webs 4 of the rails 1, 2, opposite to the splice bar 8, is a splice bar 11, which is mounted between the projections 10. The splice bar 11 is formed with a longitudinally extending opening 12 through which projects the tongue 9, the latter extending beyond the outer face of the splice bar 11 and being formed with a vertically disposed opening 13, having projecting therethrough a retaining plate 14. Carried by the outer end of the tongue 9, as well as engaging therewith, is a holding member 15 in the form of a set screw, and which is adapted to project into the openings in the plate 14 to prevent vertical movement of the latter.

When the splice bars 8, and 11 and the retaining member 14 are mounted in position, they are seated upon the bases 5 of the track rails 1 and 2.

What I claim is:—

The combination with a pair of abutting track rails having the webs thereof at the opposing ends each provided with a longitudinally extending slot opening at the edge of its respective web, each of the webs further having a longitudinally extending opening spaced from the inner wall of the slot, of a splice bar positioned against one side of said webs formed with an opening, a splice bar positioned against the other side of said webs and having an integral tongue projecting through the slots of the webs and through the opening of the other splice bar, that splice bar having a tongue further provided with a longitudinal projection at each

side of said tongue, said projections extending through the openings in the webs and engaging the ends of that splice bar having the opening, a retaining member extending down through the free end of said tongue exteriorly of the splice bar having the opening, and an adjustable holding member carried by the free end of the tongue extending lengthwise with respect to the latter and en-

gaging in said plate to prevent vertical 10 movement thereof.

In testimony whereof I affix my signature in presence of two witnesses.

IVAN GROZEJ.
